No. 643,333.

Patented Feb. 13, 1900.

E. E. MYERS.

ENVELOP.

(Application filed Oct. 10, 1899.)

(No Model.)

UNITED STATES PATENT OFFICE.

EMMA E. MYERS, OF PITTSBURG, PENNSYLVANIA.

ENVELOP.

SPECIFICATION forming part of Letters Patent No. 643,333, dated February 13, 1900.

Application filed October 10, 1899. Serial No. 733,190. (No model.)

To all whom it may concern:

Be it known that I, EMMA E. MYERS, a citizen of the United States of America, residing at Pittsburg, in the county of Allegheny and 5 State of Pennsylvania, have invented certain new and useful Improvements in Envelops, of which the following is a specification, reference being had therein to the accompanying drawings.

10 This invention relates to certain new and useful improvements in envelops, and more particularly to that class known as "safety-envelops."

15 The invention has for one object the provision of novel means whereby the envelop may be conveniently sealed and opened.

Another object of the invention is to construct an envelop in such a manner that the same cannot be opened without detection, 20 and to provide novel means that will prevent the steaming of the envelop.

The invention further aims to construct an envelop of the above-described character that will be extremely simple in its construction, 25 strong, durable, and comparatively inexpensive to manufacture.

With the above and other objects in view the invention finally consists in the novel construction, combination, and arrangement 30 of parts to be hereinafter more fully described, and specifically pointed out in the claims.

In describing the invention in detail reference is had to the accompanying drawings, forming a part of this specification, wherein 35 like numerals of reference indicate corresponding parts throughout the several views, in which—

Figure 1 is a plan view of the envelop, showing in dotted lines the manner of folding the different parts and sealing the same together. Fig. 2 is a plan view showing the envelop sealed with the exception of the securing-flap, representing the envelop before 45 the letter is inserted. Fig. 3 is a vertical sectional view taken on the line 3 3 of Fig. 2. Fig. 4 is a longitudinal sectional view taken on the line 4 4 of Fig. 2.

In the drawings the reference-numeral 1 indicates the body portion of the envelop. 2 50 and 3 indicate the side wings of the same, said wings extending at an angle, as shown at 4, to the body portion of the envelop, their

lower edge 5 extending horizontally with the envelop. The wing 2 is provided with a gummed edge 6, arranged on the upper face 55 thereof, and a similar gummed edge 7 is provided on the wing 3, on the under face thereof.

The lower flap 8, provided with a gummed edge 9 on its upper face, is formed integral with and extending below the body portion 1 60 of the envelop. This flap is further provided with a lower gummed edge 12, arranged on the under face of the flap, and is adapted to engage the portion marked 13 upon the face of the securing-flap. The upper securing-flap has a gummed edge 10 and forms the upper portion of the envelop, said securing-flap being further formed at its upper extremity at an acute angle, as shown at 11.

The manner of folding my improved envelop is as follows: The wing 3 is first folded to the center of the body portion of the envelop, and the wing 2 is then likewise folded in a similar manner, being designed to overlap in the center of the envelop. The gummed edge 7 will secure the wing 3 to the wing 2, and the gummed edge 6 will secure the wing 2 to the wing 3. The lower flap 8 is then folded upwardly, the gummed sides 9 engaging the upper face of the folded wings and forming a 80 pocket for the insertion of the letter. The securing-flap is next folded, and the gummed edges thereof extend over and are secured to the body portion of the envelop, allowing the securing-flap to assume the position as 85 shown in Fig. 2 of the drawings. It will be observed that as the securing-flap extends over the body portion of the envelop the same will be engaged by the gummed portion 12 of the flap 8 at the point indicated by the reference-numeral 13 upon the securing-flap and that the latter is then turned over and sealed and the stamp placed in the upper right-hand corner, thereby forming an additional seal to the envelop. 90

It will be noted that by the peculiar construction of the herein-described envelop a number of advantages are obtained. For example, when the envelop is closed only one seam is visible—namely, the sealing-flap—the 100 back of the envelop being perfectly smooth, as formed by the body portion of the same.

It will be noted that this form of envelop will be a great protection when transmitting

valuable papers through the mails and that various changes in the details of construction may be made without departing from the general spirit of my invention.

5 Having thus fully described my invention, what I claim as new, and desire to secure by Letters Patent, is—

1. A safety-envelop as described, comprising in its construction the body portion having side wings 2, 3, formed integral with its ends and adapted to overlap when folded with each wing provided with a gummed edge for adhesion with the opposite wing, a lower flap 8 formed integral with one edge of the body portion 1 and provided with gummed edges for adhesion with the side wings, and a securing-flap formed integral with the opposite edge of the body portion with its free edge at an angle to the edges of the completed envelop, said securing-flap being provided with gummed edges and a gummed portion 13 for adhesion respectively with the body portion and the lower flap 8, as and for the purpose set forth.

25 2. The herein-described envelop having a blank comprising a body portion 1, integral

side wings 2, 3, of equal length and adapted to overlap when folded upon the body portion 1, said side wings 2, 3, being gummed respectively upon opposite edges as at 6, 7, whereby 30 when overlapped they may be secured to each other by means of the said gummed edges, a lower flap 8 adapted to fold upon said side flaps after the latter are folded, said lower flap 8 being gummed on opposite edges as at 35 9, 12, and an integral securing-flap adapted to fold upon the lower flap 8 and the side wings 2, 3 with an overlapping portion adapted to engage the opposite side of the body portion 1, the said securing-flap having the gummed edges 10 for engagement with the side wings 2, 3, the angularly-extending gummed edge 11 for engagement with the face of the body portion 1, and the gummed surface 13 for engagement with the gummed edge 12 of the 45 lower flap, substantially as specified.

In testimony whereof I affix my signature in the presence of two witnesses.

EMMA E. MYERS.
